CLAIM

The ornamental design for an extruded wiper backing strip, as shown and described.

DESCRIPTION

FIG. 1 is a perspective view of an extruded wiper backing strip showing our new design, the strip is shown broken away in the middle to indicate indeterminate length; and, FIG. 2 is a front elevational view on enlarged scale of the extruded wiper backing strip shown in FIG. 1, the rear view being identical to the front view.

1 Claim, 2 Drawing Sheets

III. 2.
